UNITED STATES PATENT OFFICE.

EMIL RENDANO, OF BROOKLYN, NEW YORK, ASSIGNOR TO FORBES TUBULAR PRODUCTS CORPORATION, OF BROOKLYN, NEW YORK, A CORPORATION OF NEW YORK.

MACHINE FOR FORMING TUBULAR BODIES.

1,394,116.

Specification of Letters Patent.

Patented Oct. 18, 1921.

Application filed April 9, 1920. Serial No. 372,423.

To all whom it may concern:

Be it known that I, EMIL RENDANO, a citizen of the United States of America, residing at city of New York, borough of Brooklyn, Kings county, New York, have invented a new and useful Machine for Forming Tubular Bodies, of which the following is a specification.

My invention relates to a machine for forming tubular bodies.

An object of my invention is to make a tube or body of a relatively narrow strip of metal spirally wound, having the spirals mutually interengaged, which will be exceedingly strong and rigid.

Another object is to provide a machine for forming engaging portions near the edges of a metal strip and bending the strip longitudinally into spiral convolutions, having the edges of the convolutions mutually interengaged.

Another object is to provide a tubular body which will be cheap to manufacture and superior in many respects to plain or corrugated tubular bodies.

Another object is to provide means for forming a strip into spiral convolutions without the use of rotating or other mandrels.

Other objects and advantages will appear as the specification proceeds.

Briefly, a machine for carrying out the above objects may consist of rolls for forming engaging or interlocking portions at the edges of a strip and a ring for bending and directing the strip longitudinally into substantially circular form and causing the circles thus formed to take a spiral form with the edges of the adjacent spirals overlapped for interengagement. A pair of rolls may be provided for pressing the overlapped edges of the strip together to interlock the convolutions.

With my machine either hot or cold rolled steel strips or other metal may be employed.

In the drawings are shown merely a preferred form of my invention.

Figure 1 is a side elevation of my machine;

Fig. 2 is a front elevation thereof;

Fig. 3 is a section taken in the plane of the line 3-3;

Fig. 4 is a fragmentary view, on an enlarged scale, of a pair of forming rolls;

Fig. 5 is a similar view of a pair of feed rolls;

Fig. 6 is a similar view of a pair of bending rolls;

Fig. 7 is a fragmentary view, on an enlarged scale, of a pair of pressing rolls;

Fig. 8 is a perspective diagrammatic view showing the various rolls having a strip passing between them;

Fig. 9 is a fragmentary view, on an enlarged scale, of a section of tube made in accordance with my invention;

Fig. 10 is a detail fragmentary view of my improved bending and strip directing device; and

Fig. 11 is a diagrammatic view showing the gearing for operating the various rolls.

Upon a suitable base 5 is mounted a standard or frame 6 for supporting the operative parts of my machine. Journaled in the frame is a pair of rolls 7, 8, suitably fastened to shafts, such as 9. Either or both of these rolls may be mounted so as to be adjustable for accommodating various thicknesses of metal. Also mounted upon the frame, preferably in a vertical position, are a pair of bending rolls 10, 11, suitably journaled upon shafts, such as 12. These rolls may likewise be adjustably mounted so as to accommodate different widths of strip.

In order to feed the strip properly between the aforesaid rolls I may provide a pair of feed rolls 13, 14, suitably adjustably mounted in the frame upon shafts, such as 15. 16, 17 are a pair of pressing rolls suitably journaled in the frame on shafts, such as 18. One or both of these latter rolls may be suitably grooved, as at 51, 52.

Mounted upon the frame is a strip bending and directing device comprising a body 95 portion 20 which may be secured to the frame in any suitable manner. In this body 20 I mount a ring 22 which is preferably of hardened steel. This ring has one edge shaped to spirally guide the strip, and that edge is preferably inclined to the direction of movement of the entering strip. 21 is a circular rib preferably formed integrally with the body 20 and is slightly spaced from the ring 22 to accommodate one bent edge of 105

- the strip in passing about the bending and directing device. The body 20 and rib 21 may be of hardened steel to resist wear, but in most cases an ordinary steel casting will suffice for the purpose. Mounted adjacent the ring 22 and the rib 21 in any approved manner as by means of screws may be one or more guides 23 for the purpose of holding a strip against the ring and body. These guides may be curved on one side as shown at 24 for the purpose of directing the strip toward the rib 21 should the edge of the strip in passing about the rib become removed therefrom.
- 15 At the upper end of this strip bending and directing device may be another guide 25 for the purpose of directing the strip from the pressing rolls into the directing device. Upon the directing device I may also mount a series of rollers, such as 26, for the purpose of guiding and assisting in bending a strip. Suitable guides, such as 27 and 28, may be mounted adjacent the rolls for properly directing the strip 25 through the machine.
- From an inspection of Fig. 11 the gearing for driving the various rolls of my machine will be understood. 29 is a driving shaft, having thereon a gear 30 meshing with a relatively large gear 31 on one of the shafts 9. Keyed upon this shaft is a smaller gear 33. Upon the other shaft 9 is secured a gear 34 of the same size as the gear 33. Upon the two shafts 15 are mounted suitable gears, such as 35, meshing with each other and driving the feed rolls 13, 14. Also secured upon the lower shaft 15 is a gear 36, of the same size as the gear 35, and between the gears 33 and 36 is mounted 40 an intermediate gear 37. Upon the two shafts 18 are mounted suitable gears 38-38 meshing with each other and driving the pressing rolls 16, 17. Also mounted upon the lower shaft 18 is a gear 39, of the same size as the gear 38. An intermediate gear 40 meshes with the gears 36 and 39. It will be obvious, due to the relative size of the gears shown and the interposition of the intermediate gears, that all three sets of 45 rolls will be rotated in the same direction. The rolls are of such size that the peripheral speed of each is substantially the same, and with gearing proportioned as shown the rolls would be of substantially 50 equal diameter.
- The shaft 29 may be driven in any suitable manner, such as by means of the pulley 41 secured thereto. Upon the shaft 29 may be mounted a hand wheel 42, for the purpose of rotating the shaft slightly in either direction by hand. 43 is any suitable form of clutch mechanism, operated by a lever 44, for starting and stopping the machine. Obviously, any form of belt shifter would 55 serve the same purpose.

The rolls 16, 17 may be journaled in boxes, such as 45, which are carried in a yoke 46. Adjusting screws 47 may co-act with the boxes 45 for adjusting the roll 16 up or down relatively to the roll 17. 70

As shown in Fig. 4, the rolls 7 and 8 are provided with annular grooves and projections for bending one edge of a strip upwardly at an angle to the strip and for bending the other edge of the strip downwardly at an angle thereto. These rolls also channel the strip, as shown at 49 (Fig. 5). These upturned and downturned edges and the channel afterward form the interengaging portions of the spiral body. 80

In Fig. 6 are shown the rolls 10 and 11, for further bending the edges of the strip so that they will slightly overstand the body portion of said strip.

In Fig. 5 is shown a strip of sheet metal 85 passing through the feed rolls 13, 14, the interengaging portions having been formed upon the strip by the two preceding sets of rolls shown in Figs. 4 and 6.

Fig. 7 shows the strip passing between 90 the rolls 16, 17, and it will be noted that the edge 50 passes beyond the outer end of one of the rolls, whereas the other edge passes within the groove 51. Within the groove 52, which is ordinarily shallower 95 than the groove 51, may be seen two interengaging edge portions of a strip receiving the final pressing operation to form the interlocked joint.

In order to support the spiral body after 100 the same leaves the machine, there may be provided a pair of rollers 53, adjustably journaled in a framework 54, supported by the standards 55. These rollers will form a rotating support for the rotating spiral 105 body as it comes from the machine.

The operation of my device is as follows:

The end of a strip of metal is first introduced into the guide 27, from which it passes between the rolls 7 and 8, where the 110 channel portion 49 and the bent edges hereinbefore described are formed. After passing between the rolls 7 and 8 the strip passes between the rolls 10 and 11, where the edges receive a further bending, as described. 115 Ordinarily, the friction of the forming rolls will be sufficient to cause the strip to progress through the machine, but, as a precaution, to prevent bending or buckling, I provide the feed rolls 13 and 14, which may engage the strip between its edges, and feed it through the guide 28 and between the rolls 16 and 17. The formed strip will enter between the rolls 16 and 17 on the left-hand side, as viewed in Fig. 7, and the upturned edge 50 will pass by the ends of 120 said rolls and will not be disturbed. The channeled portion and down-turned edge will pass into the groove 51 and be slightly crimped together. The strip, after first 130

passing between the rolls 16—17, is engaged by the bending and directing device, and the rib 21 causes the strip to be bent longitudinally into substantially circular form, 5 while the ring 22 (having an edge properly inclined to the machine or to the direction of movement of the entering strip) directs the strip in a spiral course so that the edges of adjacent convolutions will meet and overlap, 10 ready to receive the first crimping operation, which occurs when these edges pass between the rolls 16—17 in the plane of the groove 51; when the body has completed a second revolution the partially crimped 15 edges will receive a final crimping pressure in the plane of the groove 52. The rolls 16—17 serve to feed the strip around the bending device or die member 20. As a result of this method of manufacture a spiral 20 body, such as described and of any desired length, may be produced, depending merely upon the length of the strip employed. The guide 28 may be properly beveled, as at 28', 25 for guiding the strip, coming from the bending and directing device, between the rolls 16, 17.

It should be noted that the bent edge 50 of one convolution engages with the channel 49 and bent edge of another convolution, 30 and after the edges are pressed together an interlock between the convolution is formed, as shown in Fig. 9, which will be substantially smooth upon the inside and provide a spiral arch or corrugation upon 35 the outside, and this joint will be substantially water and air tight.

By reference to Fig. 7 it will be seen that, by forming the interlocked seam in a groove in one of the rolls, the several layers of metal 40 which are folded together to constitute said seam are positively locked against slippage or free movement in any direction. As will be seen, the effect of the roll surface in the bottom of the groove 51 will be to partially 45 compact the folds and true up the sides of the seam. When the seam passes through the relatively shallower groove 52, the folds thereof are further compacted and the sides further trued up. By this method of operation 50 a seam of uniform proportions, compactness and strength will be produced.

The forward end of a tube as it emerges from the machine will, of course, have a projecting edge, as shown just to the right 55 of the roller 16 in Fig. 7, formed by the extreme forward end of the strip. This end may be sheared off in order to provide a tube having a squared-off end. The same result may be accomplished by shearing off 60 a triangular piece on the proper angle from the strip before it enters the machine.

Conduits, or tubular bodies made according to my method may be used for a great variety of purposes, such as, for example, 65 ash cans, barrels, kegs, so-called "salaman-

ders", etc., and, in fact, for any purpose where a strong, rugged, tubular body is required.

While I have described a preferred form of machine in great detail, I wish it to be understood that many modifications may be made, all coming within the scope of the appended claims.

I claim:

1. In a machine of the character described, means for bending the edges of a strip at an angle to the strip, a device including a ring having an inclined edge and a rigid rib spaced from said ring for forming the strip longitudinally into spiral convolutions with the adjacent edges of the convolutions interengaged, and a pair of rolls 75 geared together and positioned adjacent said devices for pressing the edges together to interlock the respective convolutions with 80 each other, said rolls being so positioned as to cause the edges of the strip to pass twice between them.

2. In a machine of the character described, means for forming engaging portions on 90 the edges of a sheet metal strip, an annular forming device for receiving said strip upon the inside thereof and forming the latter into interengaged spiral convolutions and comprising a substantially circular rib for 95 bending the strip into circular form, and a ring having an edge inclined to the direction of movement of the entering strip for engaging one edge of the latter and bending it into spiral form and a pair of rolls for receiving 100 said strip and forcing the latter about the inside of said annular device for forming the convolutions, said rolls serving also to press the interengaged edges of the convolutions for locking them together to 105 form a tube.

3. In a machine of the character described, a pair of rolls for bending the edges of a strip at an angle to the strip, a second pair of rolls between which the bent strip is 110 adapted to pass, one bent edge of the strip passing beyond the end of one roll, one of said rolls having a groove to accommodate the other bent edge of the strip, and a device for bending the strip longitudinally into a 115 series of spiral convolutions and causing the bent edges of adjacent convolutions to be interengaged, said interengaged edges passing twice between said pair of rolls for bending the interengaged edges for locking the 120 convolutions together.

4. In a machine of the character described, a pair of rolls for bending the edges of a strip at an angle to the strip, a second pair of rolls between which the bent strip is adapted to pass, one bent edge of the strip 125 passing beyond the end of one roll, one of said second mentioned rolls having a plurality of circumferential grooves, and a device for bending the strip into a series of 130

- spiral convolutions and interengaging the adjacent edges of said convolutions, one of said grooves and coöperating roll slightly crimping the interengaged edges and the other of said grooves and coöperating roll finally crimping the interengaged edges.
5. In a machine of the character described, means for forming engaging portions at the edges of a strip, means for 10 bending the strip longitudinally into a series of interengaging spiral convolutions, including a rib for bending the strip into substantially circular form, and a ring for bending the strip in a spiral and guiding the same so 15 as to cause the engaging portions thereof to mutually interengage, means for pressing the engaging portions to form a conduit and a rotating support for the conduit as it emerges from the machine.
- 20 6. In a machine of the character described, a pair of rolls for forming a channel in and bending the edges of a strip, means for guiding a strip to said rolls, a second pair of rolls for bending the edges 25 of the strip at an acute angle to the strip, a pair of feed rolls engaging the strip intermediate the edges, a pair of rolls one of which has a plurality of grooves for accommodating the bent portions of the strip, 30 a device including two spaced rings to accommodate one bent edge of the strip between them, one of said rings bending the strip longitudinally into substantially circular form and the other of said rings bending the strip into spiral form and guiding the latter so as to cause the bent portions 35 and channel on the strip to interengage, said strip passing once between said last mentioned rolls then about said device, and then passing a second time between said last mentioned rolls.
7. In a machine of the character described, a device including an annular body portion, a rib on said body portion for bending a strip into substantially circular form, and a ring in said body portion and having one edge inclined relatively to the direction of movement of the entering strip, said inclined edge engaging one edge of the strip for causing the latter to form one convolution of a spiral, said rib and ring being adjacent to but spaced from each other, the space between said rib and ring being provided to accommodate one bent edge of the strip.
8. In a machine of the character described, a device for bending and forming a strip into interengaged spiral convolutions comprising a body portion having a substantially circular part upon the inside for bending a strip longitudinally into circular form and a ring positioned adjacent to but spaced from said substantially circular part, said ring having an edge inclined to the direction of movement of the entering strip and engaging one edge of the latter for forming the strip into a spiral, said inclined ring and substantially circular part being spaced apart to accommodate one edge of a strip, and a pair of rolls for forcing the strip about said device and crimping the edges of the interengaged spiral convolutions.

EMIL RENDANO.
